UNITED STATES PATENT OFFICE

JOHN A. RYMER, OF BERKELEY, CALIFORNIA, ASSIGNOR, BY MESNE ASSIGNMENTS,
TO RY-LOCK COMPANY, LTD., OF RENO, NEVADA, A CORPORATION OF NEVADA

DOOR LOCK

Application filed March 8, 1929. Serial No. 345,508.

The invention relates in the present embodiment to locks of the latch bolt type having an axially slidable spindle for actuating the latch bolt, a knob on one side of the door fixedly engaging the spindle and a knob on the other side of the door releasably engaging said spindle. It will be noted that in such type of lock, in the normal position thereof both knobs engage the spindle where-
5 by it may be freely operable from either side of the door but upon a proper axial displacement of the spindle, the outer knob will be released from operative engagement with said spindle so that the latch bolt may then
10 only be actuated from the outer side of the door, by key controlled means associated with the outer knob.

One of the objects of the present invention is to provide a lock of the character de-
20 scribed which is so designed that locks embodying the same structure and tumbler barrels may be used on a plurality of doors without at the same time entailing the dis-
advantage of having every key which may
25 rotate all tumbler barrels likewise operate every lock.

Another feature, or object, of the invention is to provide a lock of the class described in which, upon the axial displacement of the
30 spindle to release the outer knob from operative engagement therewith, independent means will automatically function to lock the spindle in displaced position whereby no amount of jarring will operate to release the
35 spindle.

A further object of the invention is to pro-
vide a particularly effective means of locking the outer knob against movement when the spindle has been operatively disengaged
40 therefrom.

A still further object of the invention is to provide a lock of the class described having a spindle of readily detachable portions whereby portions of varying length may be
45 substituted to suit doors of differing thicknesses without necessitating the dismantling of the lock.

Yet another object of the invention is to provide, in a lock of the class described, a
50 particularly efficient means for insuring the

return of the outer operating means to normal position after the latter has been operated and the latch bolt has been retracted.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to said drawings,

Figure 1 is a fragmentary plan section taken through the lock and a door on which the lock is mounted, the latch bolt casing showing in plan and not in section.

Figure 2 is a vertical section of the lock taken on the line 2-2 of Figure 1.

Figure 3 is a cross sectional view of the knob taken in the plane indicated by the line 3-3 of Figure 1.

Figure 4 is a cross sectional view of the knob, taken in the plane indicated by the line 4-4 of Figure 1.

Figure 5 is a side view of the spindle and associated parts, the latter showing in section.

Figure 6 is a perspective view of several of the parts shown in Figure 5, said parts being shown separated for clearness.

Figure 7 is a view similar to Figure 3 but showing the parts in different operative relation.

Figure 8 is a plan view of parts as shown in Figure 1 but with the spindle shown released from the outer knob.

Figure 9 is a sectional view in the same plane as Fig. 1, showing the key operated member modified whereby a different key will be required to operate same.

The present embodiment of my invention is incorporated in a lock 8 disposed in a suitable cavity 9 provided in the free edge portion 11 of the door 12, and which is arranged to be operated from the inner and outer sides of the door by means of knobs 13 and 14. The lock is provided with a bolt 16 which

is arranged to normally extend from the outer end of a bolt casing 17 mounted in the door edge 11.

Slidably mounted in the casing 17 is a bolt 5 yoke or latch plate member 18 for actuating the bolt 16, such member being here shown hollow and of generally rectangular outline and being urged to assume and maintain an outer position by reason of a spring 19 operatively engaged behind it. Journalled in the casing 17 to extend horizontally therethrough is a latch actuator 21 having extending therefrom intermediate the casing walls an arm 22 arranged for engagement with the 10 latch plate 18 in such manner that a rotation of the actuator from the normal position shown in Figure 2 will effect a retractive displacement of the latch plate. Preferably, and as shown, the actuator arm 22 is 15 arranged for engagement with the latch plate both at upper and lower sides thereof whereby a rotation of the actuator in either possible direction may retract the latch plate.

Extending axially through the actuator is 20 an opening 23 arranged for the slidable reception of the spindle 24, the opening and spindle being of like polygonal section whereby rotation of the actuator may be effected by rotating the spindle. Rotation of the 25 spindle is arranged to be effected by means of the inner and outer knobs 13 and 14, the former of which is fixedly secured to the spindle by means of a screw 26 and is slidably and rotatably disposed in the escutcheon plate 27 positioned against the inner side of the door.

The spindle extends through a cavity 28 of the door, which is combined with the cavity 9. Covering the cavity 28 and positioned 30 against the inner and outer surfaces of the door are side plates 29 and 31 which secure the lock in position. The plates are connected together by means of screws 32 extending from the plate 29 and engaging in 35 segmental-shaped arms 33 fixed to the plate 31. As clearly shown in Figure 1, the plates are concealed within the inner escutcheon 27 and an outer escutcheon 34, the latter being interposed between the outer surface of 40 the door and inner edge of the outer knob.

Preferably, and as will be more fully hereinafter explained, the spindle is, for the purpose of easily adapting the lock for doors of different thicknesses, formed of two sections 45 36 and 37 which are connected together by means of cooperating hook and eye members 38 and 39 respectively formed on the sections, said members having interengaging sides to prevent relative rotation of the sections in 50 attached position. Preferably detachably secured to the outer knob such as by a bayonet connection and locked in such position by a member 41, is a knob sleeve 42 which as here shown extends through the plate 31. Oper- 55 ative connection between the spindle and

sleeve to permit rotation of the former by the outer knob is effected by means of a lug 43 extending transversely from the spindle section 37 and arranged in protracted or forward position of the spindle to engage in a notch 44 formed in the rear end of the sleeve. It will be evident that with the lug seated in the notch, as is the case in Figure 5, the outer knob may be used to effect a retraction of the latch bolt, whereas when the spindle is moved to its retracted position the lug will be withdrawn from the notch and the knob will be ineffectual to operate the bolt.

The spindle in the present embodiment of the invention is arranged to be urged to assume its protracted position, and as here shown, the same is effected by means of a spring 46 which is interposed between a suitable stop at the forward end of the spindle section 37 and a bearing wall 47 which is held against axial displacement in the sleeve but is freely revoluble therein. The spindle extends through an opening 48 of the wall, such opening being polygonal to conform to the cross-sectional shape of the section 39 whereby the latter, while capable of relative longitudinal movement through the wall, is fixed for rotative movement with it.

Revolubly mounted within the outer knob casing and fixed to the bearing member 47 for rotation therewith is what may be conveniently termed a key-tip receiving member 49 which is operatively aligned with and adjoins a tumbler barrel 51 held in the knob 14. The member 49 is provided in the forward end 100 thereof with a kerf 52 which communicates with the key passage 53 of the tumbler barrel and is arranged to be engaged by the tip of a key adapted for insertion through said passage. Since the receiving member 49 is 105 not displaced by the longitudinal movement of the spindle, it will be evident that in the retracted position of the spindle, rotation thereof from the outer side of the door to effect a retraction of the latch bolt may be 110 readily effected by turning the proper key in the tumbler with the key tip engaging in the kerf. In Figure 9 I have shown the receiving member 49' provided with a slight change in the key engaging portion thereof. As here 115 shown the kerf 54 is spaced from the inner end of the tumbler barrel by a portion 56 having an opening therein wide enough to prevent contact of the sides thereof with the key. It will be evident that with a key just 120 long enough to permit insertion through the tumbler barrel and engagement in the kerf 52 of member 49, such key will not be long enough to operate a lock otherwise the same but having in place of member 49, the member 125 49' which is provided with the kerf 54. On the other hand a key which is long enough for engagement with the kerf of a lock equipped with member 49' may also be used 130 with locks having the receiving members 49,

it being noted that ample room is allowed within member 49 for the accommodation of the longer key.

A system of locks in which only certain keys will operate all the locks and others only some locks, may thus be provided for by a practical duplication of the lock and tumbler mechanism for each door, and as a consequence an economy in cost and simplicity of installation is permitted, not possible with locks of this type as heretofore constructed. While I have shown and described a system for but two different keys, it is obvious that systems involving practically any number of different keys may be arranged for by merely providing for different relations between the tumbler barrel and the key tip receiving element and using keys to correspond.

Means are provided for causing the spindle to be automatically locked against protraction when the spindle is moved from protracted to retracted position. Fixed to the spindle for longitudinal movement therewith, but allowing the rotation of the spindle relative thereto is a slide 56 having legs 57 which are confined for movement in grooves 58 extending longitudinally of and formed in the outer face of the knob sleeve 42. Positioned between the slide and side plate 31 and secured to the knob sleeve is disc 59 upon which is mounted a pawl 61 urged inwardly by means of a spring 62. When the spindle is in protracted position the pawl lies coplanar with and bears against the edge of the slide, as clearly shown in Figure 3. However, as the spindle is retracted the slide and lug are moved past the pawl whereby the latter will automatically slip between the lug 43 and edge of the sleeve, it being noted that, as here shown, the lug is arranged to engage the pawl during the retractive movement of the spindle to prevent inward movement of the pawl before the lug has moved past same. With the pawl thus locking the spindle against forward movement, it will be clear that even when the door or locks are subjected to violent jolts, the spindle will not be released to allow the retraction of the bolt by means of the outer knob. On the other hand the release of the spindle may be readily effected from the inside of the door by rotating the inner knob whereby the lug will be moved from engagement with the pawl, such as indicated in Figure 7, and then rotating the knob to bring the lug to engage the cam edge 60 of the pawl so that the pawl may be moved outwardly sufficient to allow the return of the slide in coplanar relation therewith.

Particularly effective means are provided for holding the outer knob locked against movement when the spindle is in retracted position. Formed on the slide 56 is a projection 63 which is arranged, when the pawl is disposed in front of the lug 43, to seat in

a notch 64 provided in a forward extension 66 of the latch yoke 18. With this arrangement, while the outer knob is thus prevented from being rotated when the spindle is retracted, the inner knob may still be rotated to retract the bolt if desired, since upon the initial rotation of the inner knob the latch yoke will be moved to withdraw the extension 66 from engagement with the projection 63. It will also be evident that upon return movement of the yoke the extension 66 will move back to reposition the projection in the notch.

Means are also provided for urging the outer knob to assume and be retained in such position that when not in use, the slide 56 which, it will be remembered, is slidably secured to the sleeve of the knob, will be in position to properly engage the latch yoke when the spindle is moved from protracted to retracted position. Fixed to the sleeve is a plate 67 between which and the plate 31 is interposed a torsion spring 68. Both ends of the spring in the position of rest of the knob 14 are engaged with projections 69 and 71 respectively fixed to the plates 31 and 67. However, when the knob is turned in one direction or another, one or the other of the spring ends will be caused to move with the projection 71. When the knob is released the spring end which has been moved with member 71 forces the latter back until said end abuts the projection on the side plate at which time the knob will be disposed in normal position.

Owing to the fact that the section 36 of the spindle is formed separate of the section 37, it will be seen that the lock may be applied to doors of different thicknesses without necessitating the dismantling of the more involved operating mechanism of the lock, that is, the portion associated with the spindle section 37. By forming the sections separate, as particularly shown here, the only variation in the lock necessary to accommodate different door thicknesses is the variation in the length of the spindle section 36 and the change in the position of the slide to retain the proper relationship with the latch yoke 18. It may be mentioned, in connection with the latter matter, that when the lock is used on doors of greater proportions than that disclosed herein, so that more space between the latch casing and side plate 31 is provided, the pawl may simply operate entirely with the lug rather than with both the lug and slide.

I claim:

1. In a lock, a latch plate, a rotary spindle for actuating said plate arranged to be moved longitudinally from protracted to retracted position, means operable from the outer side of the door for rotating the spindle and arranged to be operatively connected with or disconnected from the spindle in the respective positions aforesaid, and means independ-

ent of the said plate automatically operable upon the retractive movement of the spindle for locking the spindle against protraction.

2. In a lock, a latch plate, a rotary spindle for actuating said plate arranged to be moved longitudinally from protracted to retracted position, means operable from the outer side of the door for rotating the spindle and arranged to be operatively connected with or disconnected from the spindle in the respective positions aforesaid, means independent of said bolt automatically operable upon the retractive movement of the spindle for locking same against protraction, and means co-operating with said plate to lock said first means against movement in the retracted position of the spindle.

3. In a lock, a latch plate, a rotary spindle arranged to be moved longitudinally from protracted to retracted position, means operable from the outer side of the door for rotating the spindle arranged to be operatively connected with or disconnected from the spindle in the respective positions aforesaid, an actuator on said spindle for retracting the latch plate, a spring pressed member operable automatically upon the retractive movement of the spindle to engage the same and hold it against protractive movement and means on the spindle engageable with said member arranged upon the rotation thereof to release said member, and means associated with the latch plate arranged to hold said first means against movement in the retracted position of the spindle.

4. In a lock, a latch plate, a rotary spindle arranged to be moved longitudinally from protracted to retracted position, means operable from the outer side of the door for rotating the spindle, means on the spindle arranged in the protracted position aforesaid to engage said first means and lock the same for rotative movement with the spindle, and a spring pressed member arranged upon the retractive movement of the spindle to operatively engage said last means to prevent the protraction of the spindle.

5. A lock in accordance with claim 4 characterized by the second mentioned means arranged upon the rotation of the spindle in retracted position to move said spring pressed member to release the spindle.

6. In a lock of the character described, a latch plate, a rotary spindle arranged to be moved longitudinally from protracted to retracted position, a knob on the inner side of the door secured to the spindle, a knob on the outer side of the door having a sleeve thereon, means on the spindle arranged in the protracted position to engage the sleeve whereby rotation of the spindle may be effected by the outer knob, means on the latch plate arranged to hold said sleeve against rotation in the retracted position of the spindle, and key controlled means within said

knob operable to rotate the spindle when the spindle is retracted.

7. In a door lock, a latch plate, a rotary spindle arranged to be moved longitudinally from protracted to retracted position and comprising detachably connected sections, one of which extends through said plate, a knob at the inner side of the door secured to said section, a knob at the outer side of the door having a sleeve enclosing the other spindle section, and co-operating means on said sleeve and one of said sections arranged to lock the sleeve for rotation with the spindle when protracted and to release the sleeve from rotation with the spindle when retracted.

8. In a door lock, a latch plate, a rotary spindle arranged to be moved longitudinally from protracted to retracted position and comprising sections detachably connected together against relative rotation, one of said sections operatively engaged with said latch plate and extending through the door, an inner knob connected to said section for rotating and moving same longitudinally, an outer knob having a sleeve, means on one of said sections arranged in the protracted position of the spindle to lock the sleeve for rotation therewith, and means secured to the sleeve and first section respectively against rotation and longitudinal displacement and arranged in the retracted position of the spindle to operatively engage said latch to lock said sleeve against rotation.

9. In a door lock, a latch plate, a rotary spindle arranged to be moved longitudinally from protracted to retracted position, and comprising detachable sections, one of which extends through the door and operatively engages with said latch plate, a knob on the outer side of the door having a sleeve enclosing portions of each of said sections, means on one of said sections arranged for engagement with the sleeve for locking the latter for rotation with the spindle when protracted, means connected with the sleeve and spindle to engage the latch plate to prevent the rotation of the former while the spindle is retracted, a tumbler barrel carried by the knob, and a key tip receiving member within said sleeve operatively aligned with said barrel and secured for rotation to the spindle.

10. In a door lock, a latch plate, a rotary spindle for operating such plate arranged to be moved longitudinally from protracted to retracted position, an inner knob fixed to the spindle for rotating and moving same longitudinally, a knob at the outer side of the door, cooperating means on the spindle and knob whereby the latter will be locked to the spindle for rotation therewith when protracted and operatively disconnected therefrom when retracted, a tumbler barrel carried by the knob, and a key tip receiving member connected with the spindle for rotation

therewith and rotatable independently of said barrel.

11. In a door lock of the character described, a fixed member, a rotatable knob, and means for urging and retaining said knob in fixed relation to said member comprising a torsion spring having the ends thereof normally engaged with said plate and member, one of said ends being held for or against movement with the knob according to whether the knob is rotated in one direction or another, while the other of said ends is arranged to be held against or for rotation with the knob upon rotation of the knob as aforesaid.

12. In a door lock of the character described, a latch plate, a rotary spindle for actuating said plate, a knob arranged to be operatively connected to or disconnected from said spindle in different positions of the latter, a tumbler barrel carried with said knob having a key passage, a rotatable key tip receiving member secured for rotation with said spindle and having the key engaging portion thereof arranged for operative registration with said passage, said tumbler barrel being rotatable with or without said member.

13. In locks of the character described, a latch plate for each lock, rotary spindles for actuating same, like tumbler barrels mounted for rotation in the independent locks and having key passages, key tip receiving members arranged for cooperation with the respective barrels and operatively fixed to the spindles, the portions of said members arranged for engagement by the key tips being in the different locks in different relation to the barrels whereby a key operative to rotate each of said barrels may operate but one of said members.

In testimony whereof, I have hereunto set my hand at Oakland, California, this 27th day of February, 1929.

JOHN A. RYMER.
